UNITED STATES PATENT OFFICE.

HENRY WHITE, OF MARION, OHIO.

LIME AND SEDIMENT EXTRACTOR.

SPECIFICATION forming part of Letters Patent No. 766,750, dated August 2, 1904.

Application filed May 6, 1903. Serial No. 155,868. (No model.)

To all whom it may concern:

Be it known that I, HENRY WHITE, a citizen of the United States of America, and a resident of Marion, in the county of Marion and 5 State of Ohio, have invented certain new and useful Improvements in Lime and Sediment Extractors, of which the following is a specification.

My invention relates to improvements in 10 lime and sediment extractors for use in connection with means for delivering water to boilers or other steam apparatus. The separation of the lime and sediment from the water is accomplished by delivering the water 15 from the feed-pipe into a device adapted to effect a partial purification thereof, and from thence the water is delivered to a second device, wherein it is further purified and from whence it is discharged into the boiler, 20 or other receptacle, the extracted sediment and lime being conveyed away by means of a discharge-pipe.

My invention is particularly designed, 25 therefore, to prevent foaming of the water in the boiler and the scaling thereof and tends to retain the boiler in a cleanly condition.

To this end my invention consists in certain 30 novel features of construction and combinations of parts, such as will be more fully described hereinafter, and particularly pointed out in the claims.

The figure of the accompanying drawing is 35 a side elevation of my improvements applied to a boiler, parts being broken away.

35 A indicates a horizontally-disposed boiler to which my invention is connected. It is obvious, however, that the boiler may be either vertical or inclined without affecting the scope of the invention in the slightest particular. The boiler is provided with the usual steam-dome 1.

The feed-water pipe is designated at F and 40 extends from any suitable source to a casing E, with the upper end of which the pipe communicates by means of the elbow-union G and the short length 2. This purifying-casing 45 comprises a body portion 3, preferably cylindrical and provided with annular shoul-

ders 4 4 at either end. A cap H is secured to the flange or shoulder at the upper end of 50 the casing by means of bolts p p and is provided with a collar 5, secured around the short length 2. A base I is secured to the lower annular flange 4 in a manner similar to the means for securing the cap H and is also 55 provided with a threaded collar Q in alignment with the collar 5 of the cap and adapted to be secured upon the connecting-pipe L. This connecting-pipe L may extend upwardly through the collar Q and some distance into 60 the casing E and is adapted to support a series of purifying receptacles or funnels J J of gradually-increasing size and dimensions, the smallest of which is supported upon the closed upper end of the pipe L, the next 65 largest below and separated a suitable distance therefrom, and so on, the largest receptacle being at the bottom. This arrangement, it will be observed, permits the periphery of the largest receptacle to extend laterally into 70 a vertical plane beyond that occupied by the next largest of the series, and so on. The short length 2 may be provided with a spreader or sprayer for the water, and the pipe L is provided near its point of exit from the casing E with a plurality of apertures K, whereby communication between the interior of the casing and the interior of the pipe is maintained.

Located within and extending from end to 80 end of the boiler is a separating-pipe B, the upper portion of which is provided with a series of apertures O O. The ends of the separating-pipe extend through suitably-packed bearings in the heads 6 6 of the boiler and are 85 provided with caps C C, apertured to receive a rod D, which extends through the entire length of the separating-pipe for securely retaining the pipe in position and serving as an additional support therefor. The ends of the 90 rod D are provided with adjusting-nuts 7 7 for retaining the caps tightly in place.

The separating-pipe extends through the steam-space of the boiler at a suitable distance above the water-line W.

95 The connecting-pipe L communicates with

the separating-pipe B, as does a sediment-pipe M, provided with a valve N, whereby the lime, sediment, and other impurities extracted from the water may be washed out of the casing and separating-pipe and conveyed away.

The operation is as follows: The water is admitted to the casing E through the feed-pipe F and is discharged thereby into the first 10 of the purifying funnels or receptacles J, which soon overflows, permitting the surplus water to fall over its edge into the next largest receptacle below and in like manner to the next until from the lowest and largest receptacle it falls to the base I of the casing E, and when the water has acquired a sufficient depth it overflows into the pipe L through apertures K, located a little distance above the base I. This continuous overflow permits the impurities to settle in the pans or receptacles J and also on the base I, so that the partially-purified water is conveyed by the pipe L to the separating-pipe B, wherein the impurities are further extracted, and through the 25 perforations O O of which pipe the water is discharged into the boiler, the feed-pipe, the casing, and separating-pipe, together with the sediment-pipe, being under boiler-pressure, and the water passes through the steam in the 30 separator-pipe and casing, whereby the adhesive quality of the lime is neutralized and the lime and impurities caused to settle in the sediment-pipe M. The heavier impurities will settle in the receptacles J J and in the 35 bottom of the separating-pipe B, from whence they may be washed into the sediment-pipe M when the valve N has been opened.

It will be observed that instead of utilizing the entire device as shown either the casing 40 and its connected parts or the separating-pipe may be used independently of the other, but with a less degree of efficiency. It will further be observed that many changes might be made in the form and arrangement of the 45 parts described without departing from the spirit and scope of my invention, and hence I do not wish to limit myself to the exact construction set forth; but,

Having thus fully described my invention, 50 what I claim as new, and desire to secure by Letters Patent, is—

1. The combination with a boiler, of a purifier comprising a casing, a pipe communicating with the upper portion thereof, a conveyer-pipe to which the casing is secured, the conveyer-pipe extending thereinto, a series of separating-receptacles secured upon the conveyer-pipe within the casing, a perforated separating-pipe, the ends of which are received in and project through the heads of the boiler, the conveyer-pipe communicating with the separator-pipe at one of its projecting ends.

2. The combination with a boiler, of a purifier comprising a casing, a feed-pipe communicating with the upper end thereof, a conveyer-pipe to which the casing is secured and by which it is supported, a series of separating-pans secured to the conveyer-pipe within the casing, and a perforated separator-pipe 65 located in the boiler, the conveyer-pipe extending to and communicating with the separator-pipe.

3. The combination with a boiler, of a water-purifier comprising a casing, a perforated 75 conveyer-pipe leading from the boiler and projecting into the casing, a plurality of sediment-collectors supported upon the conveyer-pipe and means for feeding water to the uppermost collector.

4. The combination with a boiler, of a water-purifier comprising a casing, a feed-water pipe communicating with the upper portion thereof, a conveyer-pipe projecting into the casing from the lower portion thereof, an apertured separating-pipe located within the boiler, the conveyer-pipe communicating therewith and a series of separating-receptacles located within the casing, the conveyer-pipe provided with apertures formed in that 85 portion within the casing.

5. The combination with a boiler, of a water-purifier comprising a casing, a series of separating-pans located therein, means connected with the upper portion of the casing 95 for supplying water thereto, means connected with the lower portion of the casing for supplying steam thereto, an apertured separating-pipe located in the boiler, the steam-conveying means connecting the casing and separating-pipe, the casing and separator-pipe operating under boiler-pressure.

6. The combination with a boiler, of a water-purifier comprising a casing, means for supplying the casing with feed-water, means 105 located in the casing for purifying the water, a conveyer-pipe upon which the casing is mounted and supported, the conveyer-pipe projecting into the casing and provided with apertures in the projecting portion, a perforated separating-pipe located within the boiler and communicating with the conveyer-pipe.

7. The combination with a boiler, of a separating-pipe located within and extending from end to end thereof, the opposite ends of 115 the separating-pipe projecting outside the heads of the boiler, caps located on the ends of the pipe, a rod passing through the caps and separating-pipe, adjusting means secured on the ends of the rod and abutting the caps, 120 means for supplying the separating-pipe with water and a sediment-pipe connected to the separating-pipe.

8. The combination with a boiler, of a casing, means for supplying water thereto, purifying means located within the casing, a 125

conveyer-pipe projecting into the casing and provided with apertures in the projecting portion, a separating-pipe located within and above the water-line of the boiler, the conveyer-pipe connecting the casing and separator-pipe, and a sediment-pipe also communicating with the separating-pipe.

Signed at Marion, Ohio, this 25th day of April, 1903.

HENRY WHITE.
